UNITED STATES PATENT OFFICE

RALPH D. GIVEN, OF LEAMINGTON SPA, AND HAROLD F. JEFFERSON, OF RUGBY, ENGLAND, ASSIGNORS TO GENERAL ELECTRIC COMPANY, A CORPORATION OF NEW YORK

APPARATUS FOR RECORDING OR REPRODUCING SOUND

Application filed January 27, 1931, Serial No. 511,594, and in Great Britain January 30, 1930.

Our invention relates to apparatus for recording or reproducing sound and particularly to the driving means for such sound record apparatus. It is the object of our invention to provide an improved sound record driving means whereby fluctuations in the speed of the driving source may be prevented from being transmitted to the record.

We have chosen to illustrate our invention as applied to a phonograph and in accordance therewith the turntable, which is constructed to constitute in effect an inertia member or flywheel, is driven through a worm and worm gear and the worm is mounted so as to have a limited axial yielding movement but is resiliently restrained from such movement. To prevent hunting we provide damping means which is associated with the worm. The damping means preferably is of the dash-pot type using oil and is located in the same oil containing casing which encloses the worm drive.

Our invention will be better understood from the following description taken in connection with the accompanying drawing, and its scope will be pointed out in the appended claims.

Referring to the drawing, Fig. 1 is a view showing the complete apparatus, and Fig. 2 shows a portion thereof which is partly a sectional view and is drawn to a larger scale.

From the drawing it will be seen that the turntable spindle 1 is driven by means of the worm-wheel 2 secured to the spindle and meshing with the worm 3 which in turn is secured to the shaft 4. This shaft is journalled in the enclosing casing 5 and has a limited amount of longitudinal movement. The movement of shaft 4 is controlled by means of the springs 6 and 7 which embrace the rod 8 secured to the arms 9 and 10 which are loosely mounted on shaft 4. Arm 9 is so secured to shaft 4 and rod 8 that any longitudinal movement of the shaft is communicated through arm 9 to rod 8. Each spring engages at one end the arm 11 attached to the enclosing casing 5 and at their opposite ends, the springs are adjustably connected with the rod 8 by means of adjusting nuts 12 and 13. The turntable 14 is

shown formed as a relatively heavy flywheel whereby irregularities in its speed are substantially avoided and consequently a sudden acceleration or deceleration of the speed of rotation of the shaft 4 causes the shaft to move longitudinally under the control of the springs 6 and 7, which springs tend to return it to its normal position. The longitudinal movement of shaft 4 is permitted by the interposition of the flexible coupling 15 (see Fig. 1) between shaft 4 and the motor shaft 16. For driving the turntable we have shown in the present case the electric motor 17 direct connected to the shaft 16. The coupling 15 is shown as comprising the cone disk 18 secured to the shaft 16 and a flexible diaphragm 19 secured at its periphery to the disk 18 and having the shaft 4 attached at its center. Diaphragm 19 may, for example, consist of an elastic material such as rubber which may be reenforced with cambric or a similar material. The elasticity of the diaphragm tends to prevent the transmission of any vibration in the shaft 16 to the shaft 4 as well as permitting axial movement of the shaft 4.

In order to prevent hunting of the shaft 4, we have provided a damping arrangement which preferably is of the dash-pot type. This is shown as comprising the piston 20 attached to the rod 21 which is secured to the lower end of the arm 9, the piston 20 working in the cylinder 22 which is filled with a suitable fluid such, for example, as oil, a path being provided between each end of the cylinder through the transverse ports 23 and the longitudinal port 24. In the port 24 there is provided the adjustable valve screw 25 which enables the port 24 to be throttled to give the exact amount of damping required. In order to prevent loss of oil the dash-pot cylinder 22 is immersed in the oil contained in the casing 5 which provides the necessary lubrication for the worm drive for the turntable. Light spring ball valves 26 are provided to permit automatic replenishment of any oil lost from the dash pot.

The turntable may be resiliently mounted by making the base pad 28 of flexible material such, for example, as cork. The cork pad 28 may in turn be seated on the base plate 29.

which if desired may be provided with an adjustable mounting to permit of the alignment of the shafts 4 and 16.

It is to be noted that while we have shown and described the gears 2 and 3 as a worm wheel and worm respectively, any other form of gearing may be used, such, for example, as spiral gears, wherein the driving force has a component in the axial direction of one of the gears and the axial movement of this gear is resiliently restrained.

We have chosen the particular embodiment described above as illustrative of our invention and it will be apparent that various other modifications may be made without departing from the spirit and scope of our invention, which modifications we aim to cover by the appended claims.

What we claim as new and desire to secure by Letters Patent of the United States, is,—

1. Phonograph driving apparatus comprising a turntable adapted to support a record disk, a worm gear connected therewith, a worm meshing with the worm gear, driving means for the worm, means for supporting the worm to permit a limited axial movement thereof, means for resiliently holding the worm in a predetermined position, and means for damping axial movements of the worm.

2. Phonograph driving apparatus comprising a turntable adapted to support a record disk, a worm gear connected therewith, a driving worm meshing with the worm gear mounted to have limited axial movement, means for resiliently opposing said movement, an oil retaining casing for said gear, and an oil dash pot device connected with said worm and arranged to operate with the oil in said casing.

3. Phonograph driving apparatus comprising a turntable adapted to support a record disk, a worm gear connected therewith, an enclosing casing therefor, a worm shaft journaled therein, a worm on said shaft in mesh with said worm gear and having a limited axial movement, a rod slidably mounted in said casing and connected with said worm, and springs associated with said casing and said rod for yieldably maintaining the worm in a predetermined position.

4. Phonograph driving apparatus comprising a turntable adapted to support a record disk, a worm gear connected therewith, a worm meshing with the worm gear, an oil retaining enclosing casing for said gear and worm, a drive shaft secured to said worm and journaled for rotary and axial movement in said casing, a motor having a flexible connection with said shaft, an arm rotatably mounted on said shaft, springs cooperating with one portion of said arm for maintaining the shaft and worm in a predetermined axial position, and an oil dash pot arranged in the oil

in said casing and cooperating with another portion of said arm.

In witness whereof, we have hereunto set our hands this 12th day of January, 1931.

RALPH D. GIVEN.
HAROLD F. JEFFERSON.
